UNITED STATES PATENT OFFICE.

ELBERT FOWLER, OF ATLANTA, GEORGIA.

ELECTRIC HEATING DEVICE.

1,283,137.

Specification of Letters Patent. Patented Oct. 29, 1918.

Application filed December 10, 1915. Serial No. 66,146.

To all whom it may concern:

Be it known that I, ELBERT FOWLER, a citizen of the United States, residing at Atlanta, Fulton county, State of Georgia, have invented certain new and useful Improvements in Electric Heating Devices, of which the following is a specification.

This invention relates to electric heating devices and more particularly to a device 10 adapted to generate heat and reflect it on the work, the device shown in the present embodiment of the invention being designed for the purpose of heating or melting a wafer of sealing wax.

15 The principal object of my invention is to provide a simple, light and efficient electric heating device for the above purpose which may be held in one hand, and one through which the article heated can be observed while the device is in use.

The above and other objects and the novel features of the invention will be apparent from the following description taken in connection with the drawing, in which,

25 Fig. 1 is a plan view of a heating device embodying my invention;

Fig. 2 is an enlarged longitudinal sectional view of the same, part of the handle being shown in elevation;

30 Fig. 3 is an enlarged plan view of the device showing a portion of the top thereof broken away to disclose the construction of the interior;

Fig. 4 is a cross sectional view on the line 35 4—4 of Fig. 2;

Fig. 5 is a detail view of the construction of a part of the casing or housing; and

40 Figs. 6 and 7 are, respectively, side and end views of the insulating and heat resisting supports for the resistance elements.

Referring to the drawing, the device in general comprises a body and a handle attached thereto, the body carrying the resistance elements which produce the heat and 45 the handle carrying the electrical supply wires and the switch which controls the current supplied to the resistance elements.

The body of the device consists of annular complementary top and bottom sections 50 forming a casing or housing for the resistance elements. The top of the housing consists of a plate in the form of an octagon which is stamped to form inclined upper sides 10 and 11 which meet at substantially a right angle to form the top ridge 12 of the device. The inner side 11 terminates at the

center in a vertical flange 13 which surrounds the sight opening 14 at the center of the device. An inner annular plate similar in outline to the plate forming the sides 10 and 11 is stamped to provide the sides 15 and 16 forming the inside top wall of the housing for the resistance elements. The sides 15 and 16 meet at an angle 17 and are spaced a distance from the sides 10 and 11, respectively, the space between the sides being filled with a suitable heat insulating material 18, such as asbestos. The inner edge of the side 16 is bent upwardly as at 19 and secure to the inner side of the flange 13 by a row of rivets 20. The side 15 is spaced from the side 10 by a row of rivets 21 which extend along the outer edge of the device.

The bottom half of the housing is made of a plate of material stamped substantially in the same form as the top plate of the housing. The bottom plate has a side 22 formed to correspond with the side 10 and a side 23 formed to correspond to the side 11 extending inwardly and upwardly and terminating in a flange 24 at the upper end which slips inside the lower edge of the flange 13 on the top half of the body. The side 23 of the bottom half has trapezoidal openings 25 punched therein through which the heat 85 from the interior of the casing may be reflected. A plate 26 is spaced from the side 22 of the bottom of the device and has a downwardly extending flange 27 which is secured to the wall 23 by a row of rivets 28. The 90 space between the bottom 22 and plate 26 is filled with a suitable heat insulating substance 29, such as asbestos. The casing is thus lined on three sides thereof with heat insulating material which is faced with the 95 metal reflecting surfaces 15, 16 and 26. These surfaces may be polished or silvered so that the heat will be more efficiently reflected from the interior of the casing through the openings 25 in the wall 23. The 100 upper edge of the plate 26 has a flange 30 (see Figs. 2 and 5) which forms a supporting surface for a corresponding flange 31 at the lower edge of the wall 15. The wall 10 of the top half also has a depending 105 flange 32 at the outer side thereof provided with a groove 33 which is adapted to fit and snap over a bead 34 on the flange 35 of the wall 22 of the bottom of the device. The top and bottom walls 10 and 22 have corresponding extensions 36 and 37 at one side of the device which are curved so as to form the

two halves of a cylindrical recess, as shown in Figs. 2, 3 and 4, to receive the plug of insulation 38 which carries the spring terminal jacks 39 and 40, to the inner ends of which the resistance coil 41 is attached by nuts 42.

- Lateral projections formed by the extensions 36 and 37 of the top and bottom halves of the casing and the plug or block 38 form 10 a stem on the device which serves as a support for a handle which has a cylindrical ferrule forming a socket 43 adapted to fit over the outside of the extensions 36 and 37. The handle member proper consists of two 15 detachably connected hollow parts 44 and 45, formed of insulating material. The socket member 43 is connected to the part 44 and the part 45 has an opening in the end thereof to admit the wires 46 and 47, 20 which supply the electric current for heating purposes. The wire 46 is connected to the inner end of a terminal post 48 which extends through the end of the handle section 44, and the wire 47 is connected to the 25 spring plate 49 on the inner side of the handle section 44. The spring plate 49 carries a button 50 by means of which the plate may be forced inwardly against a contact plate 51, which is connected to another 30 terminal post 52 extending through the end of the handle section 44. The outer ends of the terminal posts 48 and 52 are adapted to be inserted in the ends of the spring jacks 39 and 40 to complete the electrical connection 35 between the wires 46 and 47 and the resistance coil 41. The handle section 44 is formed with a boss 53 which surrounds the opening through which the button 50 projects, the outer edge of the boss 53 extending 40 beyond the end of the button 50 so that the latter will not be pushed inwardly and the circuit accidentally closed when the device is carelessly laid on a table or other support.

The resistance 41 consists of a continuous 45 coil of suitable resistance wire which is strung through openings 54 in the insulating supports 55, the construction of which is shown in Figs. 6 and 7. The insulating supports 55 are located at suitable points in 50 the annular chamber or housing of the body, in the present arrangement being disposed on radial lines passing through the angles of the octagonal housing. The plates 55 have the enlargements 56 at the outer ends 55 thereof to provide shoulders 57 on opposite sides of the plates whereby they are detachably secured in place in the angles of the casing.

From the foregoing description it will be 60 seen that the device is constructed so that it may be inexpensive to make and easily assembled and taken apart for inspection or repairs. By simply removing the handle, the socket member 43 is disengaged from the 65 extensions 36 and 37 and the plugs 48 and 52

are pulled out of the jacks 39 and 40, and then the top half of the housing may be pulled off as the latch formed by the groove 33 and bead 34 and the slip-fit between the flanges 13 and 24 only frictionally hold the 70 parts together. When the top half is removed the entire resistance coil is accessible.

The operation of the device will be apparent from the foregoing description. When it is desired to heat a body such as a 75 wafer of wax, the button 50 is pushed in to complete the circuit and the heating device is then held centrally over the wafer. The heat generated by the resistance coil is reflected outwardly by the surfaces 15, 16 and 80 26 and through the openings 25. By looking through the central opening 14 of the device the article to be heated can be watched and the device may be properly manipulated to concentrate the heat rays 85 upon the article.

While I have shown the body of the device as octagonal in form, I do not wish to be limited to this design as a circular or other suitable form may also be used, nor 90 do I wish to be limited to the exact details of the other features of the construction as shown and described since they may obviously be varied without departing from the spirit of the invention.

Having thus described the invention, what is claimed and desired to be secured by Letters Patent is:

1. A portable device for heating wafers of sealing wax and the like comprising a 100 substantially annular electrical heating element, a suitable support for said element, and a reflector back of said element and arranged to converge the heat rays upon a wafer or other object arranged centrally below the device, said reflector having a central opening through which the operation of the device may be observed.

2. An electric heating device comprising a hollow annular casing having openings in 110 one wall thereof, a substantially annular resistance element in said casing, and means for reflecting the heat generated by said resistance element through said openings.

3. An electric heating device comprising 115 a hollow annular casing having a substantially annular open portion in the bottom thereof, a substantially annular resistance element in said casing, and a reflecting surface in said casing opposite said opening 120 and back of said resistance element and adapted to reflect through said opening the heat generated by said resistance element.

4. An electric heating device comprising 125 a hollow annular casing having a portion of the wall thereof lined with heat insulating material and the remaining portion of the wall being substantially open, a heat reflecting surface opposite said substantially open portion of the wall, and a resistance 130

element in the casing in front of the heat reflecting surface.

5. In an electric heating device, the combination of a hollow annular casing having 5 a central sight opening through which the article to be heated may be observed, said casing having a substantially open side, a resistance element in the casing, and a reflecting surface in the casing adapted to reflect through said substantially open side and 10 toward the axis of said sight opening heat generated by said resistance element.

6. In an electric heating device of the class described, the combination of a hollow 15 casing comprising two separable members having interfitting portions and provided at one side with complementary projections adapted to form a stem for the attachment 20 of a handle, a resistance element in said casing, and a handle detachably mounted on said complementary projections.

7. In an electric heating device, the combination of a hollow casing comprising two separable members having interfitting portions 25 and provided at one side with complementary parts forming a cavity, an insulating plug in said cavity, spring jacks carried by said plug, and a resistance element in said casing and connected to said 30 jacks.

8. In an electric heating device, the combination, of a hollow casing comprising two complementary separable members having interfitting portions and annular in shape to 35 provide a sight opening at the center of the device for observing the work heated, means for detachably connecting said members, an electrical resistance element in said casing, and means whereby electric current conductors are connected to said resistance element. 40

9. In an electric heating device, the combination of a hollow casing, an electrical resistance on the interior thereof, spring jacks connected to the ends of said resistance, a 45 hollow handle for said device, plug members carried by said handle and adapted to be inserted in said jacks, electric conductors extending into said handle, and an electric switch in said handle and comprising an operating button extending through a hole in the handle, said handle having a boss thereon surrounding said opening and extending beyond the outer end of said button to protect the latter from accidental operation when 55 the device is laid down.

10. In an electric heating device of the class described, the combination of a hollow casing having a reflecting surface therein and an opening opposite said reflecting surface, an electrical resistance element in said 60

casing in front of said reflecting surface and comprising a continuous coil of resistance wire extending back and forth in the casing a plurality of times, and a plurality of heat insulating non-conducting plates 65 located at spaced points in said casing and having perforations through which said coil is strung.

11. In an electric heating device, the combination of a hollow metal casing comprising 70 top and bottom complementary annular members having interfitting portions at the center, and also having complementary projections on one side forming a handle stem and interfitting parts on the opposite 75 side detachably connecting the parts together, an electric resistance element in said casing, an insulating member in said handle stem, spring jacks carried by said insulating member and connected to said resistance element, a detachable handle provided with a ferrule forming a socket fitting said stem, and plugs in said socket fitting said jacks. 80

12. In an electric heating device of the class described, the combination of a hollow 85 annular casing comprising annular complementary members having interfitting top and bottom portions provided with complementary extensions forming a cavity for an insulating block and also forming a stem for 90 a handle, an electric resistance coil of continuous wire extending back and forth in said casing, a plurality of spaced heat insulating, non-conducting perforated plates in said casing and forming supporting means 95 for said resistance coil, said coil extending through the perforations of said plates, an insulating block in the aforesaid cavity, spring jacks on said block and connected with said resistance coil, a hollow insulating handle having a ferrule providing a socket at one end of the handle adapted to fit said stem, plug members in said socket adapted to fit said jacks, electric conductors, extending into said handle and adapted to 100 be connected with said plug members, a switch in said handle, a push button for operating said switch and extending through an opening in said handle, said casing having an open portion and a heat reflecting 110 wall opposite said open portion, the annular shape of the casing providing a central sight opening through which the work operated on may be observed, said reflecting wall being adapted to reflect heat generated by 115 said coil toward the axis of said sight opening.

In testimony whereof I affix my signature.

ELBERT FOWLER.
